Patented Dec. 28, 1920.

John Russell Bastedo.

Proprietor

UNITED STATES PATENT OFFICE.

HELEN RUSSELL BASTEDO, OF NEW YORK, N. Y.

DESIGN FOR AN INSIGNIA OR BADGE.

56,799.

Specification for Design.

Patented Dec. 28, 1920.

Application filed November 13, 1919. Serial No. 337,871. Term of patent 14 years.

To all whom it may concern:

Be it known that I, HELEN RUSSELL BASTEDO, a citizen of the United States, residing at 98 Park avenue, in the borough of Manhattan, city of New York, and State of New York, have invented a new, original, and ornamental Design for an Insignia or Badge, of which the following is a specification, reference being had to the accompanying drawing, forming a part thereof.

The figure is a plan view of the insignia or badge showing my new design.

I claim:

The ornamental design for an insignia or badge as shown.

HELEN RUSSELL BASTEDO.
